UNITED STATES PATENT OFFICE

EDWARD F. HARPER, OF PHILADELPHIA, PENNSYLVANIA

FORM FOR MOLDING CONCRETE AND CEMENT

Application filed May 17, 1928. Serial No. 278,485.

This invention relates to a steel or other metallic form to be used in place of lumber, in poured concrete or similar work so as to affect material saving both in the cost of 5 labor and material.

It is further aimed to provide a novel construction made up of units or sections which may be secured together by means provided thereon and in combination with battens. 10 It is further aimed to provide a novel construction wherein a sectional unit may be used interchangeably for vertical or horizontal work so that the sections may be built up according to the shape and size 15 of the proposed erection.

More specific objects and advantages will become apparent or be pointed out in a consideration of the description following taken in connection with accompanying drawings 20 illustrating an operative form.

In said drawings:—

Figure 1 is a view in side elevation showing a form constructed from the units constituting the present invention, adapted to 25 have concrete poured therein to form an arch;

Figure 2 is a plan view of the parts of Figure 1;

Figure 3 is a fragmentary side elevation 30 of the columns and deck elements, the latter being separated to accommodate a central column;

Figure 4 is a sectional view taken on the line 4—4 of Figure 2;

Figure 5 is a sectional view taken on the line 5—5 of Figure 1;

Figure 6 is a sectional view taken on the line 6—6 of Figure 1;

Figure 7 is a sectional view taken on the line 7—7 of Figure 1;

Figure 8 is a sectional view taken on the line 8—8 of Figure 1;

Figure 9 is a perspective view of one of the sections or units employed in the form; 45 and

Figure 10 is a perspective view of another section or unit employed in the form.

Referring specifically to the drawings, the form shown is illustrative of the fact 50 that the different sections or parts may be

used to build up forms for columns A and for a deck B, each being hollow as best seen in Figure 2 and adapted to have concrete or the like poured therein.

In making up the forms, a plurality of 55 generally rectangular sections designated 10 are used. Each of these sections consists essentially of a metallic sheet 11, for instance of steel, which has a backing of wood 12 suitably fastened thereto by nails, rivets, 60 bolts or other fastening means as at 13. Each plate 11 has preferably two struck out corrugations or ribs as at 14 for strengthening purposes especially under the stresses imposed when pouring concrete into the 65 form. These sections or units 10 may be of any length and width or size desired. Along one longitudinal side edge, each unit 10 has a plurality of latch members 15 pivotally connected thereto as at 16 and each 70 having a slot at 17 to engage stationary latch or keeper members 18 which may be rigidly fastened as at 19 to the opposite longitudinal side edge portions of the units.

It will be seen as shown in Figure 9 that 75 some of the units have the pivoted latches 15 along one edge and the stationary latch members 18 along the other edge. Other units 10, as shown in Figure 10, have the pivoted latches 15 along each longitudinal 80 edge, those along one edge being outwardly offset by means of blocks or the like 19^a fastened to the plates 11. It will thus be seen that the units may be arranged in pluralities so as to form the columns A or the 85 deck B with the latches 15 engaging adjacent stationary latches 18 to hold the units against displacement. In the case of the uppermost unit forming the deck, latches may be omitted at the upper edges. 90

In order to secure the units together at their ends, the reenforcing ribs or corrugations 14 are cut off short of their ends to provide shoulders as at 20 which are engaged by strips or battens 21, for instance of wood. 95 The battens are also supported by brackets 22 fastened to the plates 11 at the ends of the units. Such brackets have outer portions 23 which overlap the battens so that they will be held in place. 100

The elements 23 have openings 24 there-through whereby nails, spikes or the like may be driven into the battens. It will be seen therefore that the battens 21 where used between sections overlap the ends thereof and the junction lines therebetween.

5 The meeting ends of the units forming the deck B, as in Figure 1, may be supported or braced by a suitable structure C arranged in contact with the adjacent batten 21.

10 As shown in Figure 3, the form may be assembled, leaving a space as at D between the units forming the deck B so as to accommodate the building up of a central column in the form and its connection therewith.

15 Various changes may be resorted to provided they fall within the spirit and scope of the invention.

I claim as my invention:—

20 1. A form of the class described comprising units, latch means securing the units together, said units having reenforcing members terminating short of their ends to provide shoulders, battens for securing the sections together end to end engaging said shoulders, and brackets on the sections engaging said battens.

25 2. A unit for forms of the class described comprising a plate adapted to be secured to adjacent plates, said first plate having a re-enforcing member, said member terminating short of one end of the first plate to provide a shoulder for engagement with a batten, and bracket means on the first plate to also engage such batten.

30 3. A unit for use in a form of the class described comprising a plate, latch means along longitudinal edges of the plate, brackets adjacent an end of the plate for engagement with a batten, and reenforcing means for the plate terminating short of said end to provide shoulders to engage the batten.

35 4. A unit for use in a form of the class described comprising a metallic plate adapted for connection to adjacent plates, said plate having an integral reenforcing member terminating short of both ends thereof to provide shoulders, said shoulders being adapted to engage battens, and brackets adjacent one end of the plate to also engage the adjacent battens.

In testimony whereof I affix my signature.

EDWARD F. HARPER.
